UNITED STATES PATENT OFFICE.

FRANK W. MILLER AND JOHN D. STOFÉR, OF MONTEZUMA, OHIO.

DESIGN FOR A WASHBOARD.

SPECIFICATION forming part of Design No. 23,932, dated January 1, 1895.

Application filed December 7, 1894. Serial No. 531,155. Term of patent 14 years.

To all whom it may concern:

Be it known that we, FRANK W. MILLER and JOHN D. STOFÉR, citizens of the United States, residing at Montezuma, in the county 5 of Mercer and State of Ohio, have invented a new and original Design for Washboards, of which the following is a specification.

The invention relates to a new and original design for wash-boards.

10 The object of the present invention is to provide an attractive and useful wash-board; and the essential feature resides in a wash-board, having a transversely concavely curved rubbing surface, provided with parallel trans- 15 verse ribs, intersected at regular intervals by grooves.

In the drawings: Figure 1 is a perspective view of a wash-board showing our new and original design. Fig. 2 is a horizontal sec- 20 tional view of the same.

Referring to the drawings, 1 designates a

wash-board having a transversely curved or concaved rubbing surface 2, which is provided at regular intervals with parallel transversely disposed ribs 3, which are intersected at regular intervals by longitudinally disposed 25 grooves 4. The spaces between the transverse ribs are intersected at regular intervals by short longitudinally disposed ribs.

It will thus be apparent that the wash-board 30 is both attractive and useful.

What we claim is—

The design for a wash-board herein shown and described.

In testimony that we claim the foregoing as 35 our own we have hereto affixed our signatures in the presence of two witnesses.

FRANK W. MILLER.
JOHN D. STOFÉR.
